SELF-SEPARATING ELECTRICAL CONNECTOR

Filed May 26, 1949

UNITED STATES PATENT OFFICE

2,532,538

SELF-SEPARATING ELECTRICAL CONNECTOR

Horatio H. Burt, Hartsdale, Carl E. Soderstrom, New York, and William W. Koenig, Flushing, N. Y., assignors to Winchester Electronics Company, New York, N. Y.

Application May 26, 1949, Serial No. 95,476

1 Claim. (Cl. 173—328)

1
This invention relates to a self-separating cable connector.

It is an object of the present invention to provide a self-separating connector employing male and female contact terminals wherein the male contact elements include a rejector for the disengagement of the female sleeve contact from the male contact upon the insulating parts being released from one another, which requires upon the assembly of the male contact into the insulating member or part but a single retaining washer or clip, the rejecting sleeve being retained upon the male element against an enlargement shoulder on the element.

It is another object of the present invention to provide a self-separating connector for cables wherein the means for retaining the insulated parts containing the contacts together includes a central ground terminal fixed to one of the connector parts at the center thereof and having an internally threaded portion receiving a screw serving to secure the connector parts together, the screw extending to the outer end of the connector and bearing against receptacle portions housing the cable wires.

Other objects of the present invention are to provide a quick and self-separating connector which is of simple construction, inexpensive to manufacture, has a minimum number of parts, compact, easy to install in a wall opening, and efficient in operation.

For other objects and for a better understanding of the invention, reference may be had to the following detailed description taken in connection with the accompanying drawing, in which

Fig. 1 is a fragmentary and longitudinal sectional view of the connector embodying the features of the present invention.

Fig. 2 is an end elevational view of the connector.

Fig. 3 is an enlarged fragmentary and sectional view of the male and female contact terminal parts.

Fig. 4 is a perspective view of the retaining element or clip.

Referring now to the figures, **10** represents an insulating part adapted to contain male contact assemblies **11** circumferentially spaced throughout the insulating part in circumferentially spaced openings **12**. This male contact assembly includes a contacting surface **13**, **Fig. 3**, a shoulder portion **14** serving to limit the outward movement of an ejector sleeve **15** slideable upon a shank portion **16** which has a reduced portion **17** lying in a narrowed part of opening **12** and a

5 groove **19** adapted to receive a retaining clip **21** for making secure the assembly within the opening **12** and against action of a spring **22** which serves to keep the ejector sleeve **15** extended outwardly over the contacting surface **13**. A cable wire can be connected to a projection **23** having spaced enlargements **24** and **25**. Enlargement **26** abuts the clip **21** to prevent the inward movement of the assembly. This male contact assembly will be assembled upon the part **10** by placing the ejector sleeve **15** upon the shank **16**, thereafter the spring **22** and finally extending the assembly into the opening with the reduced portion **17** through the narrow part of the opening **12** so as to locate the clip **21** in place within the groove **19**. Thereafter cables can be connected to the portions **23**.

10 **20** **25**
To be coupled to the insulating part **10** with the male contact terminal assemblies is an insulating part **27** having female contact terminals **28** corresponding respectively with the male terminals **11** of the part **10**. These female contact terminals will enter the openings **12** of the male assembly of part **10** so as to permit the entry of the contact surface **13** of the male assembly thereinto. The female contact **28** is slit, as indicated at **29**, to provide the contact terminal portions with a certain amount of spring action in order that a tight frictional grip will be had upon the contact surface **13**. The female contact **28** has a flange **31** which enters a large hole **32** in the part **27** and a shank portion **33** which extends out of a reduced diameter portion of hole **32** which has a groove **34** for receiving a retaining clip **35** serving as an abutment against the outer face of the insulating part **27** to retain the contact terminal **28** against inward displacement. On the shank portion **33** are flanges **36** to facilitate the connection of a cable wire to the terminal.

40 **45**
The opening **12** in the insulating part **10** is tapered, as indicated at **37**, to receive a rubber seal ring **38**. The opening **32** in the insulating part **27** is tapered at **39** to receive a rubber sealing ring **41** whereby to provide for an air tight connection of the contact with the insulating member.

50
Within the center of the insulating part **27** is a central opening **42** having a reduced section **43** providing for a flange **44**, **Fig. 1**. A ground terminal **45** having an internally threaded portion **46** and a shank **47** which is threaded is extended through the reduced section **43** of the opening **42**. A rubber sealing ring **48** surrounds the shank portion **47** and fills the inner end of the opening **42**. A shoulder **49** on the ground terminal **45**

is brought into flush engagement with the inner face of the insulating part 27. A nut 61 is connected to the threaded shank portion 47 and bears against the flange 44 of the part 27 to, when adjusted, bring the shoulder 48 into tight engagement with the rear face of the insulating part 27. On the outer end of the shank portion 47 is a reduced portion having flanges, as indicated at 62, adapted for the connection of a ground cable wire to the terminal 45.

The insulating part 10 is fitted within a sleeve 54 having a flange 55 at one end thereof against which is brought to bear a sealing ring 56 disposed between the flange and a flange 57 on the outer end of the insulating part 10. Surrounding the sleeve 54 is an attaching sleeve 58 formed of metal and having a threaded portion 59 which extends through an opening 61 in a wall 62 such as a bulkhead of a pressurized cabin aeroplane. A threaded ring 63 is tightened upon the threaded portion 59 of sleeve 58 to secure the sleeve 58 within the opening 61, the opening 61 being enlarged to receive the locking nut 63. A rubber sealing ring 64 is disposed between a shoulder 65 and a face of the wall 62, whereby to provide a gas tight connection therebetween.

The sleeve 58 has an externally threaded portion 66 with an inwardly extending flange 67. The insulating part 27 has a flange 68 and between this flange 68 and the flange 67 of the sleeve 58 there is disposed a rubber sealing ring 69. The insulating part 27 and the flange 68 are brought into tight engagement with the flange 67 of the sleeve 58 by the threading upon the threaded portion 66 of the sleeve 58 an internally threaded retaining ring 71 having an inwardly extending flange 72 engaging with the outer face of the insulating part 27. Accordingly, the insulating part 27 through its flange connection with the sleeve 58 and through the sleeve 58 is tightly secured to the wall 62. By means of the several rubber sealing rings 41, 48 and 69, there is little chance of air leakage through the wall opening 61 or through the insulating member 27. The insulating part 27 bearing the female contacts is made fixed to the wall 62 in the manner as just described. The part 10 bearing the male contact assemblies is adjustable with its sleeve 54 in the attaching sleeve 58.

Surrounding the flanged end of the sleeve 54 and engaging with the flange 55 thereof is an internally threaded shell 74 having inwardly extending flange 75 engaging with the flange 55 of the sleeve 54. To maintain the insulating part 10 in tight fitting engagement with the sleeve 54 and shell 74 is an externally threaded ground ring 76 having a ground contact 77 thereon.

To further retain the insulating part 10 within the shell 74 is a cap 78 having a sleeve portion 79. The inner end of the sleeve portion 79 engages with a shoulder 81 extending inwardly within an opening 82 within the insulating part 10. A rubber sealing ring 83 is provided between the cap 78 and the outer end of the shell 74. The sleeve portion 79 of the cap 78 has a shoulder 84 receiving a rubber sealing ring 85. A connecting ground screw 86 extends through the cap 78 and its sleeve portion, through the opening of the insulating part 10 and is threaded, as indicated at 87, to engage with the internally threaded portion of the female ground contact 45 of the insulating part 27. By means of this screw, the insulating parts 10 and 27 are brought into close

coupled relationship, the contacts of the respective parts being placed in engagement with one another and against the action of springs 22 of the individual male contacts.

The ground screw has a head 88 thereon with a slot 89 therein and a ball 91 whereby the screw can be tightened or loosened by hand. Ground currents will pass through the ground screw 86, the cap 78, shell 74, ground ring 76 and ground terminal 77. The head 88 of the ground screw 86 has engagement with the outer face of the cap 78. The ground screw has a tapered portion 92 for engagement with the rubber sealing ring 85.

Depending from the shell 74 is an externally threaded portion 93 to which is threaded a fitting 94. The cable will enter the shell 74 through the fitting 94 and its wires can be connected with the portions 23 of the male assemblies and the ground terminal 77.

Upon disengagement of the screw 86 with the female ground terminal 45, the insulating part 10 with the male contact assemblies and the receptacle 74 coupled to it can be disengaged from the insulating part 27 and from the wall 62. The springs 22 will act upon the ejecting sleeves 18 of the male contact assemblies to separate the male contact from the female contact 28 whereupon the disengagement of the insulating part 10 and the parts coupled to it can be effected easily and without the same being frozen or stuck to the female contacts of the part 27. The contact terminals are thus self-separating.

It will thus be apparent that the ground contact elements serve as the means for the securing of the male and female contacts in engagement with one another. It should be further apparent that all of the parts are provided with sealing ring connections to prevent the leakage of air either between the fittings and the wall opening or through the fittings or the openings thereof. Accordingly, an air tight connector has been provided. The sleeve portion 79 of the cap 78 engages with a rubber sealing ring 85 lying within opening 82 and against inwardly extending flange 81 of the insulating part 10.

It should be further apparent that the male and female assemblies are so constructed that they can be made secure within the insulating parts by the simple extension of clips 21 and 35 over the shank portions of the contacts. To facilitate the connection of the clips with the shank portions, the insulating parts are provided with raised bosses 96 and 97 on the respective insulating parts and on their outer faces thereof.

The clip 21, Fig. 4, is of U-shape and has a central opening 98 and rounded edges projecting slightly inwardly in order to have frictional engagement with the shank portions of the contacts to prevent the easy outward displacement of the clip.

While various changes may be made in the detail construction, it shall be understood that such changes shall be within the spirit and scope of the present invention as defined by the appended claim.

What is claimed is:

An electric cable connector comprising insulating parts, each of said insulating parts having openings therein arranged in circumferentially spaced relationship and central openings, male contact assemblies mounted in the circumferentially spaced openings of one of the insulating parts, said male assemblies including spring eject-

ing means, the other insulating part having female contacts assembled in the circumferentially spaced openings thereof, the female contacts entering the openings of the male assemblies and engaging with the ejector means thereon, a female ground contact having a shank portion extending through the central opening of the insulating part having the female contacts and said ground contact being internally threaded, means for securing the insulating part having the female contacts within a wall opening, a shell assembly surrounding the insulating part having the male contact assemblies adapted to be fitted within the means securing the insulating part having the female contacts to the wall, a ground screw threaded at 10 one end thereof and extending through the shell assembly and the insulating part having the male assemblies for engagement with the female ground contact whereby to forcibly cause the engagement of the male contacts with the female contacts and to retain the same in contact relationship against the action of the ejecting means of the male contact assemblies, said means adapted to secure the insulating member having the female contacts to a wall opening including a 20 sleeve secured to the wall opening, said shell assembly surrounding the insulating member having the male contact assemblies including a sleeve surrounding the insulating member and adapted to enter the sleeve supporting the insulating member with the female contacts and an internally threaded shell member, said insulating member with the male contacts having an external flange, a ground ring threaded to the internally threaded member and engaging with the flange of the insulating member with the male contacts to retain the insulating member

with the male contacts in rigid engagement with the sleeve surrounding the same and with the shell, said shell member having a cap threaded therein with an inwardly extending sleeve portion engaging with the insulating member with the male contacts, said ground contact screw having engagement with the cap and extending through the sleeve portion thereof and engagement with the female ground contact whereby ground currents can pass to the ground ring through the ground screw, the cap, the shell member and ground ring, said shell assembly having a fitting through which cable wires may be extended for connection with the ground ring and with the male contacts.
